KENNETH P. DURHAM, OF SEATTLE, WASHINGTON

REVERSIBLE PAPER CLIP

Application filed July 30, 1929. Serial No. 382,094.

My invention relates to the art of wire clips and more particularly to that type of clip which is intended to secure a plurality of sheets together. Paper clips have been produced for a number of years in a wide variety of types, each of which are designed to accomplish a particular purpose. In my paper clip I have endeavored to produce a clip of the simplest possible form which will enable one to produce them at a minimum cost.

In some paper clips already produced, such as shown in Patent #1,378,525, sharply pointed projections are provided to enable the clip to more securely engage the papers it is to fasten together. I have found that in such a design it is very difficult to put the clip on a set of papers or remove the same without mutilating the papers.

In my clip I provide similar sharp-pointed projections but further provide that when the clip is placed on the paper or is to be removed the projections do not touch the surface of the paper. This is accomplished by having the clip so shaped and proportioned that it may be reversed after being put in position, and when so reversed will cause the pointed projections to come in contact with the surface of the paper and thus hold it securely. This reversal of the clip is in itself not new as it is shown on a clip of quite different design in Patent Number 1,317,416.

Having thus described my invention in brief, the objects I obtain with my device are namely:

First, the production of an article of manufacture which admits of very economical construction.

Second, a clip which is characterized by having pointed outward projections, which may at the will of the user be brought in contact with the surfaces of the papers to be secured together.

Third, a clip which is so constructed that it will lie flat to the paper it fastens together.

A fourth object is the production of a clip whose inner ends are so tightly pressed against the papers it secures that other papers can not be inadvertently caught under the same clip.

The above general objects of my invention

together with others inherent in the same are obtained by the device illustrated in the following drawings, the same being a preferred form of embodiment of my invention where-

55

Figure 1 is an edge view of my clip as it is normally secured to papers.

Figure 2 is a face view of the same.

Figure 3 is an edge view similar to Figure 1 except a reversal has been executed within the clip which now places the pointed projections on the outside of the clip.

Figure 4 shows my clip as applied to a plurality of papers showing the pointed projections away from the surfaces of the paper.

Figure 5 shows my clip with a reversal half completed.

Figure 6 shows the reversal completed with the pointed projections biting into the surface of the outside sheets.

Figure 7 is a sectional view taken along the line 7-7 of Figure 6.

Referring to the drawings, throughout which like numerals indicate like parts, numeral 10 designates the wire forming my clip which is bent back on itself as is shown in Figure 2. This provides a bend 11 which should be greater than the maximum thickness of papers it is designed to fasten together. The opposite ends of the wire, 12 and 14 respectively forming gripping leg portions cross at a point 16 which from my experience is shown proportionately in Figure 2.

Sharply pointed projections 12A and 14A respectively are formed on one side of ends 12 and 14 respectively. The exact position of these projections will best be understood by a careful study of the drawings, particularly of Figures 1, 2, and 3. The projections must be so located that when the clip is in the position shown in Figure 3, the inner surfaces of the ends, or more properly legs 12 and 14 must present a smooth surface for the entrance of papers.

Figure 1 which shows the clip in "reversed" position shows the pointed projections on the inside with the outside of the clip smooth. Figures 2 and 5, which are face views show rather clearly the position of the projections.

100

Method of operation

In using my clips which are normally supplied turned to the position as indicated in Figure 3, the clip should be grasped by the thumb and forefinger at the bend 11 and slid over the papers it is desired to secure together. This will put the clip in the position indicated in Figure 4. With the thumb and forefinger still on bend 11 the bend is revolved approximately 90 degrees or until it snaps into the "reversed" position. Figure 6 shows the clip in this reversed position with the outside projections pressed into the papers and holding them very securely.

15 When it is desired to remove the clip a reversal of this operation will present the smooth surfaces of ends 12 and 14 and the clip will slide off with very little effort.

Having thus described my invention and 20 its method of operation, what I claim is:—

1. A wire clip for securing sheet materials by being reversed in position thereon comprising a bend, two legs which cross, outwardly extending projections on one side of each leg so positioned as to form a toothed jaw when in the binding position.

2. A wire clip for sheet material comprising a return bend having two leg portions which cross near their extremities and outwardly extending projections on one side of said legs so located that in one position the projections point inwardly toward each other and when reversed point outwardly and away from each other.

35 3. A wire clip for sheet material comprising a return bend having two leg portions which cross near their extremities and a roughened surface on one side of said legs so located that in one position the projections 40 point inwardly toward each other and when reversed point outwardly and away from each other.

4. A wire clip for securing sheet materials together by being reversed in position thereon comprising a single wire bent back on itself so the two ends cross near their extremities and outwardly extending projections so positioned on one side of each end that they will engage the sheet material in the gripping position and will present a smooth jaw when reversed to the engaging or removing position.

55 5. A wire clip for securing sheet materials together by being reversed in position thereon comprising a single wire bent back on itself so the two ends cross near their extremities and a roughened surface so positioned on one side of each end that they will engage the sheet material in the gripping position and will present a smooth jaw when reversed to the engaging or removing position.

60 6. A wire clip for sheet material comprising a return bend having two leg portions which cross and outwardly extending projections on one side of said legs so located that in one position the projections point inward-

ly toward each other and when reversed point outwardly and away from each other.

7. A wire clip for securing sheet materials together by being reversed in position thereon comprising a single wire bent back on itself so the two ends cross and outwardly extending projections so positioned on one side of each end that they will engage the sheet material in the gripping position and will present a smooth jaw when reversed to the engaging or removing position.

In witness whereof, I hereunto subscribe my name this 25th day of July, A. D. 1929.

KENNETH P. DURHAM.
